CLOCK CASE

Richard H. Whitehead, New Haven, Conn., assignor to The New Haven Clock Company, New Haven, Conn., a corporation

Application November 30, 1934, Serial No. 755,295

5 Claims. (Cl. 58—54)

This invention relates to improvements in clock cases, and more particularly to the case-band and base construction of the case.

One object of the invention is to provide a 5 clock case capable of being simply manufactured and assembled at minimum cost.

With the above and other objects in view, this invention includes all improvements over the prior art which are disclosed in this application.

10 In the accompanying drawing, in which one way of carrying out the invention is shown for illustrative purposes:

Fig. 1 is a perspective view of a case-band and base assembled together in accordance with this 15 invention;

Fig. 2 is a fragmental front elevation of the construction shown in Fig. 1;

Fig. 3 is a fragmental sectional view on line 3—3 of Fig. 2;

20 Fig. 4 is a perspective view of the base prior to being assembled; and

Fig. 5 is a perspective view of the case-band prior to being assembled.

In the description and claims, the various parts 25 are identified by specific names for convenience, but they are intended to be as generic in their application as the prior art will permit.

Referring to the drawing, 10 is a case-band rolled up to annular form from a strip of sheet-metal, and having the case-back 11 secured thereto in a usual manner. In view of the fact that the case-band 10 is rolled up from a strip of sheet-metal, it has, in its finished form, a split or line of separation 12. On each side of the 35 split 12, the case-band is provided with a plurality of openings in the form of slots 13. The base 14 is shaped up from sheet-metal and has its top-surface 15 thereof shaped curved, as shown, to suitably fit the curvature of the case-band 10. The portion 15 of the base has struck up therefrom a plurality of tongues 16 which are spaced to correspond to the spacing of the slots 13 in the case-band. Thus, the tongues are adapted to extend up through the slots 13 and 40 be bent down, as shown in Fig. 3, to firmly secure the case-band to the base.

By virtue of this improved mode of construction, a case-band can be formed rapidly and at low cost from a strip of sheet-metal, instead of 45 forming the same from a more costly portion of an integral tube, and also more economically than would be necessary in case the band were to be formed with overlapping portions at the split 12 to form a seam.

50 This improved construction forms an efficient,

readily-assembled construction of minimum cost which, in the finished form, as will be evident when the entire clock case with bezel, dial and movement are assembled therein, will entirely conceal the split 12 and give ample strength to 5 the case-band without the need of joining the split ends of the case-band together other than is accomplished in the riveting action which secures them to the base.

The invention may be carried out in other specific ways than that herein set forth without departing from the spirit and essential characteristics of the invention, and the present embodiment is therefore to be considered in all respects as illustrative and not restrictive, and all changes 10 coming within the meaning and equivalency range of the appended claims are intended to be embraced therein.

I claim:

1. A clock case including: a clock base forming one part; a split case-band forming another part and having a minor portion of its circumference engaged against the base and with the split intermediate the ends of the area of engagement of the case-band and base, the main portion of the circumference of the case-band forming part of the outside surface of the clock case; and means adjacent and at opposite sides of said split securing portions of the case-band on opposite sides of said split, to the base. 20

2. A clock case including: a clock base forming one part; a split case-band forming another part and having a minor portion of its circumference engaged against the base and with the split intermediate the ends of the area of engagement 25 of the case-band and base, the main portion of the circumference of the case-band forming part of the outside surface of the clock case; and means integral with one of said parts and adjacent and at opposite sides of said split securing portions of the case-band on opposite sides of 30 said split, to the base.

3. A clock case including: a base forming one part; a split case-band forming another part and engaged against the base and with the split intermediate the ends of the area of engagement 35 of the case-band and base; one of said parts being provided with openings on opposite sides of said split; and means struck up from the other of said parts and extending through said 40 openings and securing portions of the case-band on opposite sides of said split, to the base.

4. A clock case including: a base forming one part; a split case-band forming another part and engaged against the base and with the split 50 55

intermediate the ends of the area of engagement of the case-band and base; said case-band being provided with openings on opposite sides of said split; and tongues struck up from the base and extending through said openings in the case-band and securing portions of the case-band on opposite sides of said split, to the base.

5. A clock case including: a base forming one part; a case-band forming another part and engaged against the base; one of said parts being provided with openings; and tongues struck up from the other of said parts and extending through said openings and securing the case-band and base together.

RICHARD H. WHITEHEAD.
